WALL PANEL

Prescott S. Huysen, Glendale, Calif.

Application May 31, 1941, Serial No. 396,607

6 Claims. (Cl. 72—16)

This invention relates to a wall panel and more particularly to a panel which is provided with a removable section adapted, when in position, to form a part of the wall.

An object of the invention is to provide a panel equipped with a removable section, the section being of the same appearance as the wall and forming a part thereof.

Another object of the invention is to provide a removable wall section supported by the wall or by a frame mounted in the wall and freely moveable therein. Yet another object is to provide a removable wall section which normally forms a part of the wall but is unattached to the wall and readily removable therefrom. Another object is to provide a frame and a plate therein to form a removable wall section, the plate being surfaced with wall material such as plaster. Still another object is to provide in a wall panel a plate carried in a frame and stop members for preventing inward movement of a portion of the plate whereby the removal of the plate may be accomplished by exerting inward pressure on another portion thereof.

A further object of the invention is to provide in a wall panel a plate carried in a frame and a stop member carried by the frame limiting the inward movement of a portion of the plate and providing a fulcrum for pivotal movement of the plate with respect to the frame. Other objects and advantages will appear from the following specification and drawing, in which—

Figure 1 is a front elevational view of the panel; Fig. 2 is a similar view with the removable section taken away; Fig. 3 is a vertical sectional view taken along the line 3—3 of Fig. 1, showing the removable section of the panel in position in the wall; Fig. 4 is a vertical sectional view like that in Fig. 3 with the removable section of the panel shown in the process of removal; Fig. 5 is a fragmentary transverse sectional view taken along the line 5—5 of Fig. 3 and Fig. 6 is a fragmentary transverse sectional view taken along the line 6—6 of Fig. 3.

In the specific embodiment of the invention described herein the assembly is shown in connection with a wall 10 supported by the usual studs 11 and 12. The wall 10 may be of any suitable composition and as shown, includes a lath 13 secured to the studs 11 and 12 and plaster 14 on the lath 13 forming the outer surface of the wall.

To the studs 11 and 12 is secured a frame 15 of metal or other suitable material. The frame 15 may be attached to the studs by nails 16 or

other means. The frame preferably includes outwardly turned flanges 17 which bound a central opening 18 in the frame. Along the sides of the frame and extending into the opening 18 are strips 19 and 20 which act as stop members and preferably extend from the lower portion of the frame to the central portion thereof.

A dished plate 21 is preferably received within the opening 18. The outward edges 22 of the sides 21 may extend along the flanges 17 of the frame 15. Preferably the edges 22 are immediately adjacent the flanges 17 but very slightly spaced therefrom. The plate is thus received within the opening 18 in the frame 15 and fits snugly therein. The very slight spacing of the edges 22 from the flanges 17 causes a small seam to appear along the edges of the plate.

The sides 23 of the plate 21 may be slightly inclined toward the central portion of the plate thus providing a greater spacing between the plate and the frame at the inner portions thereof. Preferably the sides are offset at an intermediate portion thereof to provide lateral flanges 24.

The dished portion of the plate 21 may be filled with plaster 25 or other suitable wall material. A plurality of openings 26 in the base of the plate 21 provide a key for securing the plaster to the plate.

As seen in Figs. 1 and 3, when the wall panel is completely assembled, the plaster 25, the edges 22 of the plate 21 and the flanges 17 of the frame 15 are all flush with the surface of the wall 10 and provide a smooth wall surface interrupted only by the seams around the edges 22.

In assembling the wall panel the dished portion of the plate 21 is filled with plaster or other wall material which forms a smooth outer surface for the plate and is in alignment on this surface with the outer edges 22 of the sides 23 of the plate. When plaster is used, the plaster will extend through the openings 26 in the base of the plate 21 and form keying projections 27 therein.

The plate 21 is inserted in the opening 18 in the frame 15. Since the area of the outer surface of the plate is substantially the same as that of the opening 18 in the frame 15, the plate will fit rather snugly within the frame with the lower edge 22 of the plate 21 resting on the lower flange 17 of the frame. The plate is inserted in the opening until the flanges 24 on the sides of the plate engage the stop members 19 and 20 as seen particularly in the sectional view in Fig. 6. The stop members are spaced from the outer edges

of the flanges a sufficient distance to bring the outer surface of the plate, when the flanges 24 are in engagement with the stop members 19 and 20, into exact alignment with the outer surface of the wall 10. When thus assembled, the panel presents a smooth surface which forms a part of the wall and contains no projections whatsoever.

When it is desired to remove the plate 21 from the wall, it is necessary only to press inwardly upon the upper portion of the outer surface of the plate. As seen particularly in Fig. 4, such pressure will cause the flanges 24 on the sides of the plate to pivot about the upper ends 28 and 29 of the stop members 19 and 20 respectively. The lower portion of the plate will be projected from the wall and can easily be grasped with the fingers to remove the entire plate from the wall.

The plate 21 should be of a depth substantially less than that of the flanges 17 of the frame. In other words, when the dished plate 21 and the flanges 17 of the frame are flush with the surface of the wall the frame should extend into the wall a greater distance than the plate. The difference in depth of the plate and the flanges should be sufficient to permit the plate to be moved inwardly in the removal operation, as shown in Fig. 4, without extending beyond the inner side of the frame. With this construction, the wall panel section may be placed directly above or in front of plumbing fixtures and the like without having the fixtures interfere with the movement or operation of the panel. Thus in operation no portion of the panel extends inwardly beyond the outer surface of the studding of the wall.

The removable section of the wall panel may be placed adjacent plumbing equipment in the wall or any other fixtures to which it is desired to gain access from time to time. The removable wall section serves to conceal such fixtures while at the same time permitting easy access to them. If desired, the entire wall panel may be covered with paint, paper or other covering material. When so covered the panel is completely concealed and may at the same time be readily used by breaking through the paper or other covering material.

The stop members 19 and 20 may obviously be of any suitable construction and may be located at various portions of the frame. It is important only that the stop members be disposed at an intermediate portion of the plate 21 so that they may serve the double function of limiting the inward movement of the plate and of providing a fulcrum for the pivotal movement of the plate in the removal operation.

The sides 23 of the plate 21 need not be inclined toward the central portion of the plate at the inner ends thereof but such inclination permits the edges 22 to be arranged in a position more closely adjacent to the flanges 17 without interfering with the pivotal movement of the plate when the plate is removed from the frame.

While in the foregoing description certain details of construction have been set forth for the purpose of illustration, it will be understood that variations and modifications may be made by those skilled in the art without departing from the spirit and scope of the invention.

I claim:

1. In a wall panel, a frame mounted in the wall, said frame being equipped with a central opening therein, a dished plate supported within the opening in said frame with the sides of the plate adjacent the walls of the frame around

the opening therein, said plate being movable inwardly and outwardly within the opening in the frame, the outer edges of the frame and the plate being flush with the surface of the wall when the plate is in normal position in the frame, and spaced stop members carried by the frame and extending along and in engagement with the inner surface of only a portion of the plate adjacent the opposite sides of the plate, said portion being intermediate the ends of the plate, said members being adapted to prevent inward movement of the portion of the plate engaged thereby, the other portions of the plate being free to move inwardly upon the exertion of pressure thereon whereby the plate pivots about said stop members within the frame.

2. In a wall panel, a frame mounted in a wall, said frame being equipped with a central opening therein, a dished plate removably received within the opening in the frame with the sides of the plate adjacent the walls of the frame around the opening, the plate being supported by the frame and being freely movable with respect thereto, the outer edges of the frame and the plate being flush with the surface of the wall, and a pair of stop members carried by the frame and extending along and in engagement with the inner surface of the lower portion of the plate adjacent the opposite sides thereof, said members preventing inward movement of the lower portion of the plate, the upper portion of the plate being freely movable inwardly whereby upon exertion of pressure on the upper portion of the plate the plate moves pivotally within the frame and about said stop members.

3. In a wall panel, a frame mounted in a wall, said frame being equipped with a central opening therein, a dished plate removably received within the opening in the frame with the sides of the plate adjacent the walls of the frame around the opening, the plate being supported by the frame and being freely movable with respect thereto, the outer edges of the frame and the plate being flush with the surface of the wall, the sides of the plate being offset to provide lateral extension thereof, and stop members carried by the frame in engagement with the inside surface of the extensions on only a portion of the plate, said portion being adjacent one side thereof, said stop members limiting the inward movement of said portion of the plate and providing a fulcrum for the pivotal movement of the plate within the frame.

4. In a wall panel, a substantially rectangular frame mounted in a wall, said frame being equipped with a central opening therein, a substantially rectangular dished plate equipped with openings in the base thereof to provide a plaster key, said plate being filled with plaster and being received within and supported by said frame, the sides of the plate being of a peripheral shape corresponding substantially to the inside of the frame and being disposed immediately adjacent the frame about substantially the entire periphery thereof, said plate being unattached to the frame and freely movable inwardly and outwardly with respect thereto, the outer edges of the frame and the plate and the outer surface of the plaster being flush with the surface of the wall, and a pair of spaced stop members carried by the frame and extending along and in engagement with the rear surface of the lower portion of the plate adjacent the opposite sides thereof to limit the inward movement of the lower portion of plate and to provide a fulcrum

for pivotal movement of the plate within the frame.

5. In a wall panel, a substantially rectangular frame mounted in a wall, said frame being equipped with a central opening therein, a substantially rectangular dished plate equipped with openings in the base thereof to provide a plaster key, said plate being filled with plaster and being received within the opening in said frame and supported by the lower wall of the frame about the opening, the sides of the plate being of a peripheral shape corresponding substantially to the inside of the frame and being disposed immediately adjacent the frame about substantially the entire periphery thereof, the plate being unattached to the frame and being freely movable inwardly and outwardly with respect thereto, the outer edges of the frame and the plate and the outer surface of the plaster in the plate being flush with the surface of the wall, the sides of the plate being offset to provide lateral extensions thereon, and stop members carried by the frame in engagement with the inside surface of the extensions on only a portion of the plate to limit the inward movement of said portion of

the plate and provide a fulcrum for pivotal movement of the plate within the frame.

6. In a wall panel, a frame member mounted in the wall, said frame member being equipped with an opening therein, a plate member disposed within the opening in said frame with the sides of the plate adjacent the walls of the frame around the opening therein, at least a portion of said frame extending below said plate and being in engagement therewith to provide the sole means of support for said plate within said frame, said plate being movable inwardly and outwardly within the opening in the frame and being completely unattached to said frame, and stop elements carried by one of said members and engaging a portion only of the opposite sides of the other member, said portion being intermediate the ends of the other member, the stop elements being adapted to prevent inward movement of the intermediate portion of the plate engaged thereby, the other portions of the plate being free to move inwardly upon the exertion of pressure thereon whereby the plate pivots within the frame about the stop elements.
